CLAMP FOR COLUMN FORMS

Tamis C. Schenk, Brooklyn, N. Y., assignor to
 Richmond Screw Anchor Co., Inc., Brooklyn,
 N. Y., a corporation of New York

Application March 14, 1941, Serial No. 383,291

1 Claim. (Cl. 144—291)

This invention relates to clamps for holding together form boards for the production of concrete columns and particularly angular columns such as are square or rectangular in cross-sectional shape.

The primary object of the present invention is to provide a clamp which will hold the forms square and true; which can be placed in position by one workman as distinguished from present-day column clamps requiring the services of two workmen; which is particularly adapted for small-sized columns, which will, by reason of its construction, automatically "square-up" the forms; which is light in weight, inexpensive to manufacture, and readily and easily placed in position or removed.

At the present time, the clamps used for holding column forms in place are heavy, expensive, difficult to handle and place in position and require the services of two workmen to put them in place. The device of the present invention is relatively simple, is of few parts and is easy to assemble and use.

A further object of the invention is to provide a clamp with means for adjusting it and holding it in clamping position, said means being so constructed as to prevent loosening of the clamp under vibration imposed upon it by the vibratory action imparted to the concrete while it is being poured, which vibration is also imposed upon the forms and associated elements and often tends to loosen ordinary clamp-fastening means.

These and other objects are accomplished by the invention, a more particular description of which will hereinafter appear and be set forth in the appended claim.

Reference is to be had to the accompanying drawing, in which Fig. 1 is a horizontal sectional view through a column form showing one of the improved column clamps in position thereon, the section being taken on the line 1—1 of Fig. 2, looking in the direction of the arrows; Fig. 2 is a side elevation of the structure shown in Fig. 1; Fig. 3 is a sectional view on the line 3—3 of Fig. 2, looking in the direction of the arrows; Fig. 4 is a sectional view on the line 4—4 of Fig. 1, looking in the direction of the arrows; Fig. 5 is a plan view of one of the clamping members; and Fig. 6 is a side view of the same, looking at the side indicated by the arrow 6.

In the drawing, the form within which the concrete is poured to produce a column is indicated at 1, the same being composed of a plurality of boards arranged together as disclosed in Fig. 1 and forming an angular enclosure for the con-

crete. The column may be square or rectangular or other desired angular shape. The column clamp is primarily composed of two similar angular rods 2 and 3, each rod being composed of the integrally formed legs 4 and 5, disposed at right angles to one another by bending of the rod. Thus, each of the rods 2 and 3 is adapted to extend around two sides of the form as clearly indicated in Fig. 1. When the two rods are in 10 clamping position as shown in Fig. 1, they embrace the four sides of the form and the end portions of the legs of one of the rods crosses those of the other rod. For example, when viewed as in Fig. 1, the leg 5 of the rod 2 crosses the top of the leg 4 on the rod 3, while the leg 5 of the rod 3 extends across the top of the leg 4 on the rod 2. In this crossed position the rods are 15 tightly clamped around the form and hold the form boards firmly in place, while the concrete is being poured in the form.

In Figs. 5 and 6 is shown one of the clamping members which engages the crossed portions of the rods 2 and 3, and in co-operation with adjusting nuts secured on threaded portions of said rods, 20 holds the rods clamped around the form. One of the clamping members is indicated at 6, and it will be seen that the same is provided with a tubular portion 7 provided with a bore 8 extending through it, said bore being of such diameter that 25 the clamping member may slide freely on the leg of the rod on which it is mounted. Extending laterally from the tubular portion 7 of the clamping member 6 is a lug portion 9 provided with a face 10 which abuts against one side of the form. 30 Another similar lug 11 rises above the tubular portion 7, said lug 11 abutting against that side of the form which is located at right angles to the side of the form against which the lug 9 rests. In other words, when one of the clamping members 35 is held against the form, it engages one of the corners thereof, said corner fitting into the junction 12 of the lugs 9 and 10. The clamping member 6 so embracing a corner of the form, is held in position by means of a nut 13 received on the threaded end 14 of the leg 4 of each of the rods 2 and 3.

Extending at right angles to the lug 11 is a flange 15 and a lug 16 spaced therefrom. The space between the lugs 16 and flange 15 constitutes an open-top groove or channel 17 in which the leg 5 of each of the rods 2 and 3 rests. At the upper end of the flange 15 and also at the upper end of the lug 16 is provided a laterally projecting ear 18, these two ears 18 constituting locking 50 means for the nut 13 adjustable on the threaded 55 end 14 of the leg 4.

end 20 of each of the legs 5 on each of the rods 2 and 3.

When the nuts 19 are tightened up, they will, under sufficient rotative force, snap or spring past the two ears 18 to permit the clamping members 6 to be tightened about the form and thus draw the two rods 2 and 3 tightly around the form. However, when these nuts are in the position indicated at the right of Fig. 3, with one of the corners of the nut, as indicated at 22, located between the ears 18, the ears will serve to prevent the nut from turning or rotating and thus causing it to loosen. The locking of the nut in the manner described is of considerable importance since, according to present-day practice, most poured concrete is vibrated into the forms and the vibration of the pouring devices often causes form clamps to loosen. With the present arrangement, this is prevented by the positive locking of the nuts in the manner described.

From the foregoing, the manner in which the device is used will be clearly understood. In applying the clamps, one of the rods is first placed in position with one corner of the form embraced by the clamping member 6, carried on the leg 4 of the rod. The nut 13 is then tightened up and the tightening of said nut causes the clamping member to be forced snugly against the corner of the form which is sufficient to hold the one rod in position around the form. This frees the hands of the workman so that he may apply the next rod, which first has the leg 5 dropped into the groove 17 on the clamping member of the rod already fitted into place. The leg 4 of the second rod is then swung upwardly causing the groove 17 on the clamping member carried thereby to embrace the leg 5 of the first rod. Now, the four nuts 13 and 19 are all tightened up, and the two clamping members 6 engaging diagonally opposite corners of the form will cause the rods to be drawn tightly around the form to hold the form indefinitely in position.

Since the nuts 19 will be locked by their engagement with the ears 18, the clamp will not loosen through vibration or for other reasons and will remain securely in position until manually removed from around the form.

The use of the device is such that the ends of the threaded portions 14 and 20 of the several rods may be headed after one of the clamping

members has been placed upon each of the ends 4 of the two halves of the clamp and nuts have been threaded thereon. When this is done, each half of the clamp permanently carries two nuts 5 and a clamping member so that the parts are thus maintained together and neither the nuts nor the clamping members can be separated from the rods. Since the first half of the clamp, when put in place, will maintain itself in position around the form when one of the clamping members has been tightened against the form by adjustment of the nut 13, the hands of the operator are then free to apply the second half of the clamp so that the application of the clamps around the form is a one-man job. The clamp is light in weight, relatively inexpensive to manufacture and can be used repeatedly for an indefinite number of times. Since the angle defined by the bent legs of the rod is a permanent and accurate one, the tightening 10 of the clamp around the form ensures the production of a true and square form which will remain in that condition until the clamp is removed.

What I claim is:

A clamp for column forms comprising, a rod 25 bent to form it into two leg portions disposed at right angles to and in fixed relation to one another, said legs being adapted to embrace two sides of a four-sided column form, a similarly shaped rod adapted to embrace the two remaining sides of the form whereby said two rods completely surround the four-sided form, the end portions of the first rod crossing at right angles to the end portions of the second rod, a clamping member disposed on the rods at their points of 30 crossing, only two of said clamping members located at diagonally opposite corners of the form being required to hold the two rods completely about the form, each clamping member having a tubular part formed with a bore through which 35 an end portion of one of the rods extends, said clamping member also having an open-sided slot wholly disposed to one side of the bore whereby the end portion of the other rod extends through said slot and crosses that which extends through the bore, means on the rods for adjusting the 40 same through the clamping member, and angular surfaces on each clamping member for abutment against two sides of the column form.
